UNITED STATES PATENT OFFICE.

SAMUEL FRANKSTON, OF LOS ANGELES, CALIFORNIA.

DESIGN FOR A VESTETTE.

45,088.

Specification for Design.

Patented Dec. 30, 1913.

Application filed August 14, 1913. Serial No. 784,786. Term of patent 7 years.

To all whom it may concern:

Be it known that I, SAMUEL FRANKSTON, subject of the King of Great Britain, residing at Los Angeles, in the county of Los Angeles, State of California, have invented a new, original, and ornamental Design for Vestettes, of which the following is a specification, reference being had to the accompanying drawing, forming part thereof.

The figure is a perspective view of the vestette, illustrating my new design.

I claim:

The ornamental design for a vestette as shown.

SAMUEL FRANKSTON.

Witnesses:

EDMUND A. STRAUSE,
MARIE BATTEY.
